COTTON CONDENSER SAMPLING DEVICE

George E. Gaus, Washington, D. C., assignor to
 Henry A. Wallace, Secretary of Agriculture of
 the United States of America, and his suc-
 cessors in office

Application September 12, 1938, Serial No. 229,583

4 Claims. (Cl. 19—156)

(Granted under the act of March 3, 1883, as
 amended April 30, 1928; 370 O. G. 757)

This application is made under the act of
 March 3, 1883, as amended by the act of April 30,
 1928, and the invention herein described and
 claimed, if patented, may be manufactured and
 used by or for the Government of the United
 States of America for governmental purposes
 without the payment to me of any royalty there-
 on.

My invention relates to new and useful im-
 provements in cotton condensers and pertains
 more particularly to a condenser designed to pro-
 duce a ribbon-like division length-wise of the
 sheet of lint cotton upon discharge from the con-
 denser in the form of a bat of cotton.

15 One of the objects of my invention is to provide
 means for obtaining a portioned sample of lint
 cotton entering a cotton bale box which will be
 truly representative of the bulk of the lint cotton
 composing the completed bale.

20 Another object of my invention is to provide
 means for the collection and delivery of the sam-
 ple of cotton bat obtained at a point remote from
 the plane of issuance at the cotton condenser of
 the major portion of the cotton bat.

25 The following description, considered together
 with the accompanying drawing will fully disclose
 my invention, its constructions, arrangements,
 and operations of parts, and further objects and
 advantages thereof will be apparent.

30 In the drawing:

Figure 1 is a plan view illustrating an embodi-
 ment of my invention with respect to a cotton
 condenser with the cover of its casing removed.

Figure 2 is an elevational section through the
 35 condenser along the line 2—2.

Referring with more particularity to the drawing
 in which like numerals designate like parts,
 the numeral 3 designates the casing or housing of
 an ordinary cotton condenser connected to a lint
 flue transition 4, said flue serving to conduct the
 air-borne lint cotton from the gins. The usual
 screen cylinder is replaced by a drum 5 having an
 enlarged narrow concentric portion 6. This en-
 larged portion or sample area may be either in
 the center, at one of the ends, or at any other
 suitable locus on the lateral surface of the drum
 45 5. The usual compression roller 7 is correspond-
 ingly reduced in diameter above the enlarged por-
 tion 6, substantially as shown. An endless screen
 belt 8 passes over the enlarged portion 6 and an
 idler pulley 9 at a suitable point in front of the
 condenser passing through a guide channel 10
 and an aperture 11, substantially as shown. The
 channel 10 is disposed on the lint slide 12 and em-
 braces the sides of the belt 8 substantially be-

tween the outlet of the condenser and the en-
 larged portion 6.

The end walls 13, 13 of the enlarged portion 6
 are imperforate and preferably non-collective of
 lint cotton, such as highly polished wood and so 5
 forth. These end walls extend radially and are
 beveled on their inner sides to provide peripheral
 bearings 14, 14 for the stepped ring sections 15,
 15 of the roller 7. The reduced section 16 of the
 roller 7 between the members 15, 15 is preferably 10
 perforated, but such perforations are not indis-
 pensable.

The operation of this invention is as follows:
 The air-borne lint cotton is conveyed through
 the lint flue transition 4 into the condenser cas- 15
 ing 3 where it strikes against the imperforate
 end walls 13, 13, the screen surfaces of the drum
 5, and the conveyer belt 8. The mass of air-borne
 lint cotton, striking the rotating curved, smooth,
 surfaces of the walls 13, 13, is diverted thereby 20
 to the rotating screen surfaces of the drum 5 and
 to the conveyer belt 8. The said cotton is de-
 posited on the outer screen surfaces while the air
 is separated therefrom and passes through said
 screen surfaces where it is vented from the casing 25
 3 in the usual manner known in the art. The
 lint cotton is compressed into bats beneath the
 roller 7 and they are delivered through the lint
 slide 12 in the usual manner, except that the bat
 issuing from the enlarged portion 6 is carried 30
 away on top of the belt 8 through the guide chan-
 nel 10 forming the sample bat, which is truly
 representative of the lint cotton discharged from
 the condenser. The sides of said guide channel
 10 prevent wayward air currents inter-felting the 35
 cotton fibers of the sample bat with the other
 cotton. The tangential path of movement of the
 belt 8 away from the drum 5 causes the disjunc-
 tion of any mislaid cotton fibers overlapping the
 end walls 13, 13. 40

It is to be understood that this invention may
 be modified by making the sample area 6 smaller
 than the main body of the drum 5 instead of
 larger, with corresponding changes in the roller
 7, such a modification being a mere reversal of 45
 parts within the scope of anyone skilled in the
 art. Also other types of cotton condensers may
 be employed, the type shown in the drawing being
 chosen for the purpose of illustration because it is
 one of the simplest known in the art. 50

Having thus described my invention, I claim:

1. In a cotton lint condenser, a condenser cyl-
 inder having a small portion of its lateral surface
 enlarged concentrically, a compression roller co-
 acting with said cylinder, having a portion there- 55

of recessed complementary to said enlarged portion of said condenser cylinder, a perforated conveyer belt disposed about said enlarged portion and about an idler pulley in front of the condenser, and a guide channel projecting from said enlarged section to the exterior of the condenser and embracing said belt.

5. The apparatus as defined by claim 1 in which the recessed portion of the compression roller is 10 perforated.

3. In a cotton condenser, a cylinder having a screen lateral surface and an off-set concentric portion, said off-set portion having a screen lateral surface and radially extending beveled im- 15 perforate end walls, a compression roller co-acting with said cylinder, said roller having a concentric off-set portion complementary to the off-set portion of said cylinder and co-acting there-

with, a screen conveyer belt operating on the sur- 5 face of the off-set portion of said cylinder beneath the off-set portion of said roller, and guide means embracing the sides of said conveyer belt sub- stantially between the outlet of the condenser and the off-set portion of said cylinder.

4. In a cotton lint condenser, a condenser cyl- 10 inder having a small portion of its lateral surface concentrically reduced, a compression roller co- acting with said cylinder having a portion there- of enlarged complementary with said reduced portion of said condenser cylinder, a perforated conveyer belt disposed about said reduced portion and about an idler pulley in front of the con- denser, and a guide channel embracing said belt 15 and projecting from said reduced portion to the exterior of the condenser.

GEORGE E. GAUS.
